UNITED STATES PATENT OFFICE

171,302

MICROSCOPE

Ludwig Leitz, Laufdorfweg, Wetzlar, and Heinrich Kleemann, Burgsolms, Germany, assignors to Ernst Leitz, G. m. b. H., Wetzlar/Lahn, Germany, a corporation of Germany

Application May 4, 1953, Serial No. 24,848

Term of patent 14 years

(Cl. D57—1)

To all whom it may concern:

Be it known that we, Ludwig Leitz and Heinrich Kleemann, a citizen of Germany and resident of Laufdorfweg, Wetzlar, Germany, a citizen of Germany and resident of Burgsolms, Germany, respectively, have invented a new, original, and ornamental Design for a Microscope, of which the following is a specification, reference being had to the accompanying drawing, forming a part hereof.

Fig. 1 is a perspective view of a microscope showing our new design taken on an oblique angle to the front of the microscope;

Fig. 2 is a perspective view taken from the opposite angle of the microscope; and

Fig. 3 is a front elevation of the microscope.

We claim:

The ornamental design for a microscope, as shown.

LUDWIG LEITZ.
HEINRICH KLEEMANN.
